UNITED STATES PATENT OFFICE.

LORNE A. GRIFFIN, OF ELKHART, INDIANA.

SUCTION-MACHINE FOR CONDUITS CONVEYING LOOSE, ABRASIVE, AND DISINTEGRATED MATERIALS.

1,153,684.

Specification of Letters Patent. Patented Sept. 14, 1915.

Application filed December 4, 1914. Serial No. 875,464.

To all whom it may concern:

Be it known that I, LORNE A. GRIFFIN, a citizen of the United States, residing at Elkhart, in the county of Elkhart and State 5 of Indiana, have invented new and useful Improvements in Suction-Machines for Conduits Conveying Loose, Abrasive, and Disintegrated Materials; and I do hereby declare the following to be a full and exact 10 description of the invention, such as will enable others skilled in the art to which it appertains to make and use the same.

This invention relates to suction apparatus for the conveyance of loose, abrasive 15 and more or less disintegrated material in conveyer conduits in which a jet of steam or fluid under pressure is discharged into an elbow fitting connected at one end with the discharge conduit pipe, and at its other 20 end with a suction conduit open in any suitable manner for the reception, or introduction, of the material to be handled by the conduit line.

Where ashes is the material for convey- 25 ance and a steam jet is used to create the necessary vacuum, or suction, the ash is projected violently against the bore of the elbow at all points thereof within the circle where the diverging steam jet strikes the 30 surface of the elbow bore. This condition results in uniform but heavy wear throughout the circle of the steam jet contact and necessitates the protection of the entire elbow bore at and adjacent to that point, 35 especially at the points beyond the actual points of contact.

The objects of my invention are, first, the use of a wall section, or liner, to protect the entire upper half of the elbow bore from 40 the extreme rear to the discharge nozzle, second, the use of an opening in the rear wall of the elbow for the insertion and removal of said upper liner, third, the use of removable wear liners in the lower bore of 45 the elbow to coöperate with the upper liner and which may be renewed without interference with the upper liner.

On account of the fact that the elbow top 50 may be placed against a building wall, or the side of a building, when installed in a conduit line, it becomes important to be able to insert and remove the upper liner at the rear end thereof which is seldom if ever inaccessible for that purpose. And on account 55 of the fact that one side or the other

of the elbow may be inaccessible it is important that the lower liner may be accessible from both sides thereof.

In the annexed drawings, Figure 1 is a longitudinal section; Fig. 2 is a rear end 60 elevation; Fig. 3 is a section on the line A—A of Fig. 1; Fig. 4 is a section on the line B—B; Fig. 5 is a longitudinal section of liner C; Fig. 6 is a front end view of liner C; Fig. 7 is an elevation of cover plate 65 G; Fig. 8 is a section through the same plate; Fig. 9 is a longitudinal section through the liner D; Fig. 10 is a fragmentary section showing a modified form of the upper liner.

The component parts of my invention are clearly shown on the annexed drawings wherein A is the flanged elbow body, B a removable top wear liner of segmental and semi cylindrical formation, C the forward bottom liner, D the rear bottom wear liner, E a handhole cover and plate, F a removable top cover plate, G the rear end cover plate, H the nozzle for fluid under pressure, and J and K the side cover plates. 70 75 80

When assembled for operation the elbow has inlet and discharge openings 1 and 2, respectively, for connection, respectively, with suction and discharge pipe lines.

The top wear liner B is segmental and 85 semi cylindrical in formation and of substantially uniform thickness except as shown in the modified form in Fig. 10. It is inserted to the elbow interior through the semi crescent shaped opening 3 formed in the rear 90 wall of the elbow and partially encompassing the fluid nozzle H and the opening 4 within which the nozzle is arranged. The liner insertion opening 3 is sealed by the semi crescent shaped cover plate G secured 95 in position by the studs and nuts 5. When the elbow is inclined toward or placed in a perpendicular position the plate G retains the liner B against rearward movement, or 100 displacement.

In the top of the elbow body is a rectangular opening 6 extending from the rear wall thereof to a point adjacent the discharge nozzle flange 2' opening up the elbow interior when the liner B is removed, and communicating with the semi crescent shaped opening 3. Opening 6 also communicates with the interior of the discharge nozzle 2 which is enlarged to receive the forward end of the liner B. The opening 3 is 110

substantially concentric with said discharge nozzle enlargement. The top opening 6 is sealed by the top cover plate F and the studs and nuts 7, the plate serving also as an auxiliary wear plate to save the elbow body from destruction in case the liner B is worn entirely through, by neglect, and the abrasive action is carried beyond same. The semi crescent shaped opening 3 terminates 5 at each side of the nozzle opening 4 in a floor 3' upon which the rear bottom edges of the wear liner B rest. Each floor 3' is prolonged or extended forward in the form of a longitudinally extending ledge 12 to serve 10 as a support for the liner B, terminating at the opening 10, as indicated at 12'. The front end of liner B therefore overhangs the opening 10 from 12' forward to the limit of the width thereof.

15 At the side of the inlet end 1 of the elbow is formed the handhole 8 which is closed by the double wall handhole cover E' fastened to the elbow body by the studs and nuts 9.

20 On opposite sides of and adjacent to the discharge nozzle 2 the insertion openings 10 and 10 are formed, both of which communicate with the elbow interior and are provided with the flat inclined floor 10' integral 25 with the elbow body. Each opening 10 extends longitudinally from a point adjacent the flange 2' rearwardly for a distance sufficient to accommodate the two bottom liners C and D and to admit of some play thereof.

30 Merging at the elbow interior the openings 10 and 10 form a transversely extending compartment for the accommodation of both lower liners C and D. Side cover plates J and K seal the openings 10 and 10 and also 35 prevent the lateral displacement of the liner D, being secured in position to the elbow body by the studs and nuts 11. Vertical walls 6', oppositely disposed and substantially parallel, extend from the opening 6 40 and connect same with the ledges 12 and 12.

45 When arranged within the elbow body, the front end of the liner B is held against upward displacement by the upper half circle, or archway, of the flange 2' which acts as a retaining arch. The rear end of said liner B, partially supported by the floors 3', is held against upward displacement by the arch A', also integral with A. As stated, the liners C and D are formed to permit 50 of some play in the compartment in which they are arranged and the upper edges C' and D' respectively, of said liners are slightly spaced from the lower edges B' of the liner B to permit of ready insertion and 55 removal of the liners C and D free from friction with the edges B' of the liner B.

60 Lugs C'' are formed on each side of the bottom liner C to assist in maintaining its equilibrium, being formed at a point thereon somewhat in the rear of the forward end 65 14. The hook holes 13 are provided in each lug C'' for removal purposes. The liner D is formed with lugs of a character similar to those C'' of liner C, but they must extend laterally to each side cover plate J and K 70 for light contact therewith to maintain the liner D against lateral displacement. Hook holes similar to holes 13 in liner C may be formed in liner D within which a hook may be inserted for removing same, said holes 75 being formed in the lugs, as at 13.

Bottom liner C is mounted within the elbow bore by thrusting same through either opening 10 to the elbow center and then projecting same laterally and forward into 80 the discharge opening 2 until the lugs C'' contact with the front edge of the opening 10. Thereupon, the front end 14 of the liner C will be substantially flush with the face of the discharge opening flange 2'. The 85 liner D is then inserted until its concave wear surface is in alignment with the wear surface of the liner C. In this position it is held against lateral displacement by the side plates J and K with which the liner lugs 90 lightly contact. The liner C is confined against lateral movement by the elbow body itself, and against rearward movement by the liner D.

In the modification shown in Fig. 10 the 95 forward end of the liner B is made lighter and thinner at B'' where a minimum amount of wear may occur either when the elbow and liner are very long, or when the entire fitting is used merely as an elbow without 100 the steam jet.

The rear cover plate G is semi crescent in form and is provided with stud holes 15 for engagement with the studs 5, and the semi circular opening G' within which the 105 flange H' of the nozzle H is arranged.

When the liners B and C are installed within the elbow fitting the bore thereof at the discharge opening 2 is substantially the same as the bore of the inlet opening 1, and 110 to accommodate the liners B and C therein the elbow interior at the discharge opening is enlarged in proportion to the thickness of the liners which are formed to permit of some play within the elbow body.

I claim:

1. In a suction machine for material conveying conduits of the class described the combination of an elbow body, an opening in the rear wall of the elbow, a second opening in said rear wall partially encompassing said opening; a removable segmental wear liner forming the upper half bore of said elbow arranged within same, one end of which liner is arranged within said second 120 named opening and the opposite end thereof 125 extending forward into the discharge opening of the elbow, means for supporting said

liner forward of said second named opening, and means for preventing a rearward movement of said liner.

2. In a suction machine for material conveying conduits of the class described the combination of an elbow body, an opening in the rear wall of the elbow, a second opening in said rear wall partially encompassing said opening, a removable segmental 10 wear liner forming the upper half bore of said elbow arranged within same, one end of said liner being arranged within said second named opening and the opposite end thereof extending forward into the discharge opening of the elbow, oppositely disposed and longitudinally extending ledges formed at the elbow interior adapted to support said wear liner, and a cover plate sealing said second named opening, said cover plate 20 serving also to retain said wear liner against rearward movement.

3. In a suction machine for material conveying conduits of the class described the combination of an elbow body, an opening 25 in the rear wall of the elbow, a second opening in said rear wall partially encompassing said opening and provided with oppositely disposed floors, a removable semicylindrical wear liner forming the upper half 30 bore of said elbow arranged therein, one end of said liner being arranged within said second named opening and resting upon said floors the opposite end thereof extending forward into the discharge opening of the 35 elbow, oppositely disposed and longitudinally extending ledges connected with said floors formed at the elbow interior adapted to support said wear liner, and means for sealing said second named opening said 40 means serving also to prevent the rearward movement of said wear liner.

4. In a suction machine for material conveying conduits of the class described the combination of an elbow body provided 45 with suction and discharge openings, a wear liner compartment in said elbow body adjacent the discharge opening, an opening for said compartment, removable wear liners arranged within said compartment and adapted for removal through said compartment opening, means for sealing said compartment opening, and means for preventing the lateral displacement of one of said liners, the other liner being otherwise confined against lateral displacement.

5. In an elbow for material conveying conduits of the class described the combination of an elbow body, an opening of semi crescent formation in the rear wall of the 60 elbow, a compartment in the elbow body adjacent the discharge opening thereof, ledges formed at the elbow interior, extending longitudinally thereof and terminating at said compartment, a semi cylindrical wear liner arranged within said elbow, one end of said

wear liner being disposed within the semi crescent opening and the opposite end thereof of being disposed within the discharge opening of the elbow, said wear liner being supported upon said ledges, and said wear liner being confined against upward displacement by the elbow, body itself, and means for preventing the rearward movement of said liner said means serving also to seal the opening of semi crescent formation. 75

6. In a suction machine for material conveying conduits of the class described the combination of an elbow body provided with suction and discharge openings, a transversely extending wear liner compartment in said elbow body adjacent the discharge opening, lateral openings for said compartment, removable wear liners arranged within said compartment and adapted for removal through said lateral 80 openings, cover plates for sealing the lateral openings, and means for fastening the cover plates to the elbow body. 85

7. In a suction machine for material conveying conduits of the class described the combination of an elbow body provided with suction and discharge openings, a transversely extending wear liner compartment in said elbow body adjacent the discharge opening, lateral openings for said compartment, removable segmental wear liners arranged within said compartment and adapted for removal through said lateral openings, one of said wear liners being adapted for insertion within said compartment and subsequent forward projection into the elbow discharge opening, said wear liner being confined against rearward displacement by the other liner and against lateral displacement by the elbow body, cover plates sealing said lateral openings, and means for fastening the cover plates to the elbow body. 100 105

8. In a suction machine for material conveying conduits of the class described the combination of an elbow body provided with suction and discharge openings, a wear liner compartment in the elbow body adjacent the discharge opening thereof, lateral openings for said compartment, removable segmental wear liners arranged within said compartment and adapted for removal through said lateral openings, one of said liners being adapted for forward projection beyond the forward terminal of said compartment, cover plates for sealing said lateral openings, and means for fastening said cover plates. 110 115

9. In an elbow for material conveying conduits of the class described the combination of an elbow body provided with inlet and discharge openings, said discharge opening being enlarged to accommodate wear liners, a liner insertion opening in the rear wall of the elbow, oppositely disposed ledges provided at the elbow interior and extending 120 125 130

- longitudinally thereof, a removable segmental wear section forming the upper half bore of the elbow arranged within same and supported by said ledges, said wear section having its rear end arranged within the liner insertion opening the top of which serves to retain the wear section against upward displacement, and a cover plate sealing the liner insertion opening.
10. In an elbow for material conveying conduits of the class described the combination of an elbow body provided with inlet and discharge openings, said discharge opening being enlarged to accommodate wear liners, a liner insertion opening in the rear wall of the elbow, oppositely disposed ledges provided at the elbow interior and extending longitudinally thereof, a removable segmental wear section forming the upper half bore of the elbow arranged within same and said discharge opening and supported by said ledges, said wear section having its rear end arranged within the liner insertion opening the top of which serves as an abutment against upward displacement of the wear liner, and means for preventing rearward displacement of the wear section said means serving also to seal the liner insertion opening.
15. In an elbow for material conveying conduits of the class described the combination of an elbow body provided with inlet and discharge openings, said discharge opening being enlarged to accommodate wear liners, a liner insertion opening in the rear wall of the elbow, an opening in the top of the elbow, oppositely disposed ledges provided at the elbow interior and extending longitudinally thereof, a removable segmental wear liner forming the upper half bore of the elbow arranged within same and supported by said ledges, said wear liner having its rear end arranged within the liner insertion opening and its opposite end within the discharge opening enlargement, a cover plate sealing the opening in the elbow top, and a cover plate sealing the liner insertion opening.
20. In a suction machine for material conveying conduits of the class described the combination of an elbow body provided with inlet and discharge openings, said discharge opening being enlarged to accommodate wear liners, a liner insertion opening in the rear wall of the elbow body adjacent the discharge opening and having lateral openings, removable segmental wear liners arranged within said compartment and adapted for removal through said lateral openings, cover plates sealing said lateral openings, a removable segmental wear liner forming substantially the upper half bore of the elbow and arranged within same, said wear liner having its rear end arranged within the liner insertion opening and its opposite end within the discharge opening enlargement, means for supporting said wear liner intermediate the liner insertion opening and said discharge opening, and a cover plate sealing the liner insertion opening.
25. In a suction machine for material conveying conduits of the class described the combination of an elbow body provided with inlet and discharge openings, said discharge opening being enlarged to accommodate wear liners, a liner insertion opening in the rear wall of the elbow, a transversely extending wear liner compartment within the elbow body adjacent the discharge opening, lateral openings for said compartment, removable segmental wear liners arranged within said compartment and adapted for removal through said lateral openings, oppositely disposed ledges provided at the elbow interior and extending longitudinally thereof and terminating at said compartment, a removable segmental wear liner forming substantially the upper half bore of the elbow and arranged within same and supported by said ledges, said wear liner having its rear end arranged within the liner insertion opening and its opposite end within the discharge opening enlargement, said upper liner being retained against upward displacement by the elbow body, and a cover plate sealing the liner insertion opening, said cover plate serving also as a means for preventing the rearward movement of the upper liner.
30. In testimony whereof, I affix my signature in the presence of two witnesses.
